UNITED STATES PATENT OFFICE.

DAVID L. WILLIAMS, OF TRENTON, NEW YORK, ASSIGNOR OF ONE-FOURTH TO GLEN P. DODGE
AND ONE-FOURTH TO ROY L. MEALUS, OF UTICA, NEW YORK.

SPOKE-EXTRACTOR.

No. 884,447.

Specification of Letters Patent.

Patented April 14, 1908.

Application filed April 30, 1906. Serial No. 314,557.

To all whom it may concern:

Be it known that I, DAVID L. WILLIAMS, a citizen of the United States, residing at Trenton, in the county of Oneida and State of New York, have invented certain new and useful Improvements in Spoke-Extractors, of which the following is a specification, reference being had therein to the accompanying drawing.

10 My invention relates to an improved spoke extractor, and I declare that the following is a full, clear, concise and exact description thereof sufficient to enable one skilled in the art to make and use the same, reference being had to the accompanying drawings in which like letters and numerals refer to like parts throughout.

In the drawings Figure 1 is a side view of the extractor in operative position relative 20 to a hub and spoke; Fig. 2 is a top view of the extractor; Fig. 3 is an inner end view; Fig. 4 is a cross section view on the line $x-x$ of Fig. 1, and Fig. 5 is a plan view of a portion of the device on the line $y-y$ of Fig. 1.

25 It will be understood that in using the extractor the hub is supported in the usual manner on a stand to which it is secured by a screw-bolt for the application of leverage to hold the hub firmly seated, and that the 30 outer end of the spoke may be supported by a rod, brace or other means.

Referring to the drawings in detail, A represents the hub and A' the spoke which is to be extracted. The device comprises power 35 means for clutching the spoke and similar means engaging the former means to extract the spoke. The former means comprises a yoke B of suitable form and strength, having at its base a properly formed recess to engage 40 one side of the spoke. To bear on and clutch the other side of the spoke I provide block C which is adapted to slide within the yoke on the sides b and which is operative by the screw or bolt b' to which power is applied to 45 force the block C toward the opposite end or butt of the yoke B (properly recessed for the spoke) and securely hold the spoke therebetween.

The block C has a threaded aperture to receive the lever or power rod D which is screw-threaded to be passed to and fro through the block C and which has at its outer end the lever with handles D' and at its inner end the head d' fixed on the end of the lever or power 55 rod by a loose joint of common construction

so that it can bear evenly on the surface of the hub adjacent to the spoke that is to be extracted. Connected with the yoke B and here shown as integral with block C is the support arm B'' which extends parallel with the lever or power rod D and at its outer end is adapted by the offset b'' to support the lever or power rod in its manipulation. Upon the support arm is slidably mounted a guide bracket E having yoke portions E' to receive 60 the spoke whereby the mechanism is held in position for its operation. The bracket has a thumb-screw e by which the upper members of the bracket may be slightly drawn together to engage the brace arm B'' to prevent 65 the bracket from slipping.

In operation the device is slipped onto the spoke, as indicated in Fig. 1, the lever or power rod being unscrewed so that the yoke can be brought suitably near the hub, the 70 spoke lying between the bottom of the yoke and the sliding block which is carried in the yoke. The block is then screwed downward to engage the spoke between the block and the yoke. The outer end of the spoke lies 75 between the yoke arms of the sliding bracket E whereby the device is kept from swinging to one side and is supported in a measure on the spoke so that the power is utilized to the best advantage. By means of the handles 80 D' the lever or power rod D is then screwed inward so that the head d' bears against the hub and the power rod is operative to withdraw the spoke.

It will thus be seen that I have provided a 85 simple device comprising means for clutching the spoke and means for pulling the same from the hub, whereby the spoke can be extracted without any marring of the hub or chipping the edge of it next to the spoke.

Having described my invention, what I claim as new and desire to secure by Letters Patent, is:

1. A spoke extractor comprising the following members in combination: a rigid 100 support-arm having at one end an offset apertured to loosely support a power rod and at the other end having a block screw-threaded to receive the said rod, the face of such block being adapted to engage one face 105 of a spoke, a yoke transverse the arm and having side-bars engaging the block and having the interior face of the yoke, opposite the said block, adapted to engage the other face of the spoke, a screw-bolt mounted in the 110

yoke and adapted to fix the relative position of said engaging faces, and a power-rod screw-threaded at one end through said block and supported adjacent the other end 5 in the said offset, one end of the rod having means bearing on the hub and the other having lever handles to turn the same.

2. In a spoke extractor, an arm having an offset at one end and a block at the other 10 end, a power-rod supported loosely near one end in the said offset and screw-threaded near the other end through the said block, having at the former end handles and at the other end means to bear on the hub of a 15 wheel, and a yoke mounted on the adjacent end of the arm having a spoke-engaging surface, the face of said block also having a spoke-engaging surface, and a bolt screw-mounted in the yoke adapted to clamp the 20 spoke engaging faces against the spoke.

3. A spoke extractor comprising a power-rod bearing at one end on the hub adjacent the spoke and at the other end having handles and screw-threaded for a part of its 25 length, a block adapted to engage a spoke and screw-bored to receive the said rod, a yoke having a face adapted to engage the spoke and mounted on the block adjustably transverse the line of the spoke.

30 4. A spoke extractor comprising a power-rod bearing at one end on the hub adjacent the spoke and at the other end having handles and screw-threaded for a part of its length, a block adapted to engage a spoke 35 and screw-bored to receive the said rod, a yoke having a face adapted to engage the spoke and mounted on the block adjustably transverse the line of the spoke, and a bracket slidably mounted and engaging the

40 power-rod and the spoke near its free end.

5. A spoke extractor comprising a power-rod having at one end a loose joint adapted for the bearing of the rod on the hub adjacent the spoke and at the other end having

handles and being screw-threaded for a part 45 of its length, a block adapted to engage a spoke and screw-bored to receive the said rod, an arm connected with the block and extending parallel with the power-rod and having an offset to support the power rod adjacent its outer end, and a yoke having a face adapted to engage the spoke and mounted on the block adjustably transverse the line of the spoke.

6. A spoke extractor comprising a power-rod, an arm substantially parallel with and along the side thereof having at one end a block, the said block being screw-bored and the said arm having at its other end an apertured offset, the power-rod passing through 60 said screw-bored block and the said offset and adapted to bear on the hub at one side of the spoke, a yoke formed to slide on the block, the latter being fashioned to receive the yoke, and having means to adjust 65 the yoke relative to the block to engage a spoke between the opposite face of the yoke and the block, by which combination power may be applied through means of the rod against the hub at one side of the spoke to 70 withdraw the same.

7. A spoke extractor having an arm provided at one end with a block screw-bored, a power-rod passing through the said block and adapted to bear on the hub at one side 75 of the spoke, a yoke mounted on the block adjustable transverse the line of the spoke and provided with means engaging the block to clutch the spoke between the block and the yoke, and a bracket adapted to engage 80 the spoke and the power-arm.

In testimony whereof I affix my signature in presence of two witnesses.

DAVID L. WILLIAMS.
